ATTORNEYS

UNITED STATES PATENT OFFICE.

NELLIE J. KELLY, OF VICTOR, NORTH CAROLINA.

DESIGN FOR A PLATE FOR FOOD-BOILERS.

SPECIFICATION forming part of Design No. 33,478, dated October 30, 1900.

Application filed September 29, 1900. Serial No. 31,586. Term of patent 7 years.

To all whom it may concern:

Be it known that I, NELLIE J. KELLY, a citizen of the United States, and a resident of Victor, in the county of Moore and State of North Carolina, have invented and produced a new and original Design for a Plate for Food-Boilers, of which the following is a full, clear, and exact description.

The design relates to a plate to be placed in the bottom of a pot for preventing food, except cereal foods and starch, from scorching when being boiled.

Reference is to be had to the accompanying drawings, forming a part of this specification, in which similar characters of reference indicate corresponding parts in both views.

Figure 1 is a plan view of the plate embodying my design, and Fig. 2 is a section on the line 2 2 of Fig. 1.

The design presents the appearance of a 20 body part *a* in the form of a thin plate on which appear a number of perforations surrounded by annular protuberances *b*.

Having thus described my invention, I claim as new and desire to secure by Letters 25 Patent—

The design for a plate for food-boilers, as herein shown and described.

In testimony whereof I have signed my name to this specification in the presence of 30 two subscribing witnesses.

NELLIE J. KELLY.
